(57) **CLAIM**

The ornamental design for lighted tweezers, as shown and described.

DESCRIPTION

FIG. 1 is a perspective view of the first embodiment of the lighted tweezers;

FIG. 2 is a left side elevational view thereof;

FIG. 3 is a right side elevational view thereof;

FIG. 4 is a top plan view thereof;

FIG. 5 is a bottom plan view thereof;

FIG. 6 is a rear elevational view thereof;

FIG. 7 is a front elevational view thereof;

FIG. 8 is a perspective view of a second embodiment thereof;

FIG. 9 is a left side elevational view thereof;

FIG. 10 is a right side elevational view thereof;

FIG. 11 is a top plan view thereof;

FIG. 12 is a bottom plan view thereof;

FIG. 13 is a rear elevational view thereof; and,

FIG. 14 is a front elevational view thereof.

The broken lines shown in the drawing views depict portions of the lighted tweezers that form no part of the claimed design.

1 Claim, 8 Drawing Sheets
